BASKET CARRIAGE

Helen St. John Zumwinkel, Webster Groves, Mo.

Application September 16, 1938, Serial No. 230,174

4 Claims. (Cl. 280—41)

This invention relates to a carriage for baskets of a type adapted for pick-up assistance in a self-service market.

An object of this invention is to provide a carriage capable of holding two baskets which will be collapsible, and which will be economical in construction and sturdy in service.

Another object of the invention is to provide means in connection with such a carriage for 10 moving and collapsing the upper portion of such a carriage to permit access to a lower basket.

Other and specific objects will be apparent from the following detail description, taken in connection with the accompanying drawings.

15 Fig. 1 is a perspective view of the carriage without the baskets;

Fig. 2 is a side elevation;

Fig. 3 is a detail showing the pivot connection; and

20 Fig. 4 is a detail of a bracing element.

The carriage includes a substantially rectangular frame 1, a lower U-frame 2 and an upper U-frame 3, all of which are pivoted together by pins 4.

25 The frame 1 includes side members 5, a lower cross member 6, intermediate cross members or bars 7 and 8, and a top cross member or handle bar 9.

The U-frame 2 comprises a pair of side members 10 and a lower cross member 11.

The upper U-frame 3 includes a pair of side members 12, an intermediate cross member 13, and a top cross member 14.

30 The rectangular frame member 1 with the complementary U-frames 2 and 3 comprises in effect a pair of scissor frames pivoted by the pins 4. A perfectly practical structure can be made, and has been made, by making the U-frames 2 and 3 integral with each other.

35 Means are provided for limiting the outward movement of the frames 1, 2 and 3 with respect to each other, while permitting them to be collapsed. The means specifically illustrated includes a plate 15 having outwardly extending ears 16, 17, 18 and 19. The ears 16 and 17 engage opposite edges of a side member 5 of the frame 1; the ear 18 engages an edge of a side member 10 of the U-frame 2; and the ear 19 engages the bottom edge of a side member 12 of the U-frame 3.

40 Other acceptable means are known in the art for limiting the extended portion of the frames. The upper U-frame 3 may be moved, as shown in dotted lines, Fig. 2, to provide access to a lower basket, and the lower U-frame 2 may be col-

lapsed so the device occupies a small space, when not in use.

While, as specifically shown, the frame 3 is attached to the structure by the pivot 4 which pivots the frames 1 and 2 together, it may be understood that the frame 3 may be independently pivoted to the frame 2 or to the frame 1 while securing substantially the same result, although the structure as specifically shown in this respect is preferable.

45 Rollers 20 are secured by brackets 21 to the cross members 6 and 11 on the frames 1 and 2. The particular structure and arrangement of these rollers is not a part of this invention. As specifically shown, all of the brackets 21 are pivoted to the frame members, but this may be so or not, according to individual preference. Or three rollers may be used instead of four.

The cross members 6 and 11 are arranged to engage the bottom of and form a support for a 20 lower basket or container 22 while the cross members 7 and 13 form a support for an upper basket 23.

50 Displacement of the lower basket 22 is prevented by lugs 24, supported by brackets 25, carried respectively by the cross members 6 and 11. The lugs 24 are adapted to engage in the mesh of wire forming the bottom of the basket 22. When the lugs 24 are in engagement in the mesh of the basket, accidental collapsing of the frames 30 1 and 2 with respect to each other is thereby prevented.

The upper basket is so proportioned that its side walls engage the edges of the cross members 8 and 14, thereby preventing endwise displacement of the basket and also when in position holding the frames 1 and 3 in extended position with reference to each other.

55 It has been previously stated that the frames 2 and 3 may be integral. But when they are separately hinged to the structure a convenient function is provided, as best shown in Fig. 2. Thus the top basket 23 may be removed and the frame 3 folded back, as shown in dotted lines Fig. 2, to provide more ready access to the lower basket 22.

It will be obvious that various changes may be made in the details of construction, within the scope of the appended claims, and that parts of the invention may be used without the whole.

50 I claim:

55 1. In a carriage of the character described, a pair of scissor frames collapsibly pivoted together near their central portion, supports on the frames above and below the pivot respectively for re-

movable containers, and means on the frames adjacent said supports for engagement with the containers to prevent their lengthwise displacement and to hold the frames in extended position.

5. 2. In a carriage of the character described, a pair of scissor frames collapsibly pivoted together near their central portion, supporting cross members on the frames respectively at two levels, above and below the pivot, for engagement with 10 the bottom of removable containers, and upwardly extending lugs attached to the lower part of the frames for engaging in a wire mesh bottom of the lower container.

15. 3. A carriage of the character described having a rectangular frame, a lower U-frame pivoted to the central portion of the rectangular frame, rollers secured on the bottoms of said frames, an up-

per U-frame pivoted to the aforesaid structure, supports on the lower part of the rectangular frame and the lower U-frame for a removable container, and supports on the upper part of the rectangular frame and the upper U-frame for a 5 second removable container.

4. A carriage of the character described having a rectangular frame, a lower U-frame and an upper U-frame pivoted to the central portion of the rectangular frame, means for limiting the 10 extended position of said frames while permitting the U-frames to be collapsed independently, and cross members on the frames above and below the pivot for supporting containers on two levels one above the pivot and one below.
